UNITED STATES PATENT OFFICE.

FRANK E. THOMPSON, OF STAMFORD, CONNECTICUT, ASSIGNOR TO THE YALE & TOWNE MANUFACTURING COMPANY, OF STAMFORD, CONNECTICUT.

LOCK.

Application filed January 6, 1927. Serial No. 159,414.

This invention relates to improvements in locks and more particularly those of the "cylinder" type,—one object of the invention being to provide simple means to effectually 5 lock the plug against turning upon attempted surreptitious manipulation of the lock.

A further object is to utilize a portion of the plug to provide means cooperable with the cylinder to lock the plug against turning, 10 upon attempted forcible operation of the lock.

With these and other objects in view, the invention consists in certain novel features of construction and combinations of parts as hereinafter set forth and pointed out in the 15 claims.

In the accompanying drawings:

Figure 1 is a fragmentary sectional view of a cylinder lock structure embodying my invention;

20 Figure 2 is a transverse sectional view;

Figure 3 is a fragmentary longitudinal section, illustrating the mode of operation of my improvements, and

25 Figure 4 is a detail fragmentary view of the plug.

A lock cylinder is indicated at 1 and in its inner face a groove or recess 2 is formed, for a purpose hereinafter explained and the cylinder is also provided with tumbler receiving 30 recesses 1^a. The plug of the lock is shown at 3 and is provided with a head 4 and a divided ring 5, which latter enters a groove 6 in the plug. The rib portion 3^a of the plug 3 is cut away at one end as at 7 and formed with a 35 weakened portion, as a tongue 8 projecting into the cut-away portion, and forming one of the ribs of the plug.

Normally the parts are in the positions shown in Figure 1 and the tongue will in no 40 way interfere with the normal operation of the lock, but should attempt be made to force the lock with the use of a screw-driver or other device, as illustrated in Figure 3, the weakened portion of the plug, viz, the tongue 45 8,—will be forced outwardly and a portion 8^a thereof caused to enter the recess 2 in the cylinder wall. The plug will now be in such relation to the cylinder that it will be effectually locked against turning and normal 50 operation of the lock to retract a bolt, will be prevented.

I do not in this case claim broadly means controlled by attempted surreptitious operation of the lock to block the effective operation of the bolt operating means, the same 55 being contemplated by copending application filed even date herewith and designated by Serial No. 159,422, nor broadly to means carried by the plug adapted to be caused to interlock with the cylinder, the same being 60 contemplated by copending application filed even date herewith by Frederic K. Heyer and designated by Serial No. 159,423.

Having fully described my invention what I claim as new and desire to secure by Letters 65 Patent, is:—

1. The combination of the cylinder and plug of a lock, said plug having an integral part thereof weakened and adapted, upon attempted surreptitious operation of the lock, 70 to be forced into locking relation to the cylinder and prevent the plug from being turned.

2. The combination of the cylinder and plug of a lock, said cylinder having a recess, and said plug having an integral weakened 75 part adapted to be forced into said recess upon attempted surreptitious operation of the lock.

3. The combination of the cylinder and plug of a lock, said cylinder having a recess and said plug having a tongue to be forced 80 into said recess in the cylinder to lock the plug to the cylinder upon attempted surreptitious operation of the lock.

4. The combination of the cylinder and plug of a lock, said cylinder having a recess and said plug having internal ribs, and a tongue at one end portion of the plug, said tongue forming one of the ribs of the plug and adapted to be forced to engage in the recess of the cylinder upon attempted surreptitious operation of the lock. 85

5. The combination of the cylinder and plug of a lock, said plug having a head and the cylinder having a recess inwardly of said head, said plug having a part to be forced 95 to engage in said recess and behind the head on the plug upon attempted surreptitious operation of the plug.

In testimony whereof, I have signed this specification.

FRANK E. THOMPSON.
